UNITED STATES PATENT OFFICE.

NANCY M. FITCH, OF AUBURN, NEW YORK, ASSIGNOR TO STEARNS FITCH,
OF SAME PLACE.

KILN FOR FIRING POTTERY, &c.

SPECIFICATION forming part of Letters Patent No. 281,625, dated July 17, 1883.

Application filed January 6, 1881. (No model.)

To all whom it may concern:

Be it known that I, NANCY M. FITCH, a resident of Auburn, county of Cayuga, and State of New York, have invented certain Improvements in Portable Kilns for Firing Pottery, &c., of which the following is a clear, full, and exact description, reference being had to the accompanying drawings, forming a part hereof, in which—

10 Figure 1 is a perspective, Fig. 2 a vertical section, and Fig. 3 a detail in plan, of a kiln constructed in accordance with my invention.

Heretofore portable furnaces or kilns have been constructed for the use of dentists, jewelers, assayers, and for firing pottery, and the latter have comprised a removable pot, pan, or receptacle in which the pottery is placed to be fired; and I do not claim such as of my invention, the main objects of which are to so construct a pottery-kiln as to render it capable of being readily set up for use and taken down for condensed storage or transportation, and to permit full oversight of any ware therein during the process of burning, as hereinafter 25 described, the novel features of which construction are specifically set forth in the claims.

A represents a foundation or base consisting of a single casting comprising an annular groove formed by flanges *b b* on its upper surface, central arms, *a*, and lugs *f f*. In addition to these integral elements of the base, I provide suitable legs, which are preferably removable, and a latch, *f'*, pivotally secured to the base, so as to be projected to form an 30 additional lug for the support of a grate, *g*, the perforations *g'* of which are in this instance disposed annularly, but which may extend over its entire surface, if desired. The wall of the kiln comprises two or more tiers 35 of segmental fire-bricks, *C C'*, the lower tier, *C*, resting in the groove of the base, and set to form air inlets or spaces *c*, for a purpose hereinafter stated. The segmental bricks of the remaining tiers, *C'*, are set against each other, 40 and are retained in close contact end to end and upon each lower tier by bands or hoops *e*, each of which is held in position by straps *e*, bent to enter the joint between the tiers, 45 as shown.

B represents the ware-receptacle, which is 50 of a diameter that when in position for use leaves an annular fire-space only, as the receptacle rests or stands upon the arms *a* of the base. In this instance the receptacle is divided into two chambers by a perforated shelf, *l*, 55 supported upon a flange, *l'*, formed or fastened on the inner wall. A vent and sight-tube, *K*, is provided, which projects through an aperture, *c'*, in one of the bricks *C'*, and a similar tube, *i*, is secured in the cover *L* of the receptacle.

This being the construction, the operation is as follows: To start a fire in the kiln after it is set up, as described, charcoal is ignited and swung to and fro in the open air in the 65 perforated dish *m*, and when burning sufficiently is put into the annular fire-space, the receptacle *B*, with the decorated ware therein, being in position in the kiln and covered, as shown. Coal or other fuel is now supplied, 70 and the air enters the apertures *g'* and spaces *c'* and supports combustion, and the desired heat is secured, which, being not confined to the bottom of the receptacle, has a gradual effect upon the ware within the receptacle, so 75 that it is uniformly absorbed thereby rather than forced therein by confinement to the bottom only. The main body of incandescent fuel is more broadly disposed, and the apertures and spaces for the air-supply are corre- 80 spondingly diffused or arranged, so that the heat is not only intense, but uniform. Inspection of the effect of the heat is readily secured in either chamber by the pipes *K i*, and at the proper time the latch *f'* is turned and the grate 85 *g* falls, and with it the body of burning fuel, and the ware and receptacle are allowed to cool gradually, as usual in the art.

Having described my invention and its operation, what I claim is—

1. A portable pottery-kiln comprising a base consisting of a single casting provided with upwardly-projecting annular flanges *b b*, forming a groove, a central spider or arms, *a*, and lugs *f*, and adapted to be supported on 90 suitable legs, substantially as shown and described.

2. In a portable pottery-kiln, the combina-

tion of a base comprising in a single casting the flanges *b b*, the arms *a*, and lugs *f*, with a grate *g* and latch *f'*, substantially as specified.

3. The combination of the base *A*, having the spider or arms *a*, the grate *g*, the bricks *C*, set to form spaces *c*, and the receptacle *B*, arranged or resting upon the arms *a*, substantially as and for the purpose set forth.

4. The combination of the base *A*, having arms *a*, the grate *g*, the ware-receptacle *B*, having the sight-tube *K* and cover *L*, and the band *c*, having straps *c'*, substantially as shown and described.

5. The combination of the base *A*, having arms *a* and grate *g*, the spaced bricks *C*, and the close bricks *C'*, one of which is apertured, as at *c'*, with the ware-receptacle *B*, resting upon the base, and provided with the sight-tubes *K*, shelf *i*, shelf *l*, and cover *L*, substantially as shown and described.

NANCY M. FITCH.
